UNITED STATES PATENT OFFICE

150,244

DESIGN FOR A LADY'S HANDKERCHIEF

Murray Morenstein, New Rochelle, N. Y.

Application July 18, 1947, Serial No. 140,359

Term of patent 14 years

(Cl. D3—12)

To all whom it may concern:

Be it known that Murray Morenstein, a citizen of the United States, residing at New Rochelle, in the county of Westchester and State of New York, has invented a new, original, and ornamental Design for a Lady's Handkerchief, of which the following is a specification, reference being had to the accompanying drawing, forming part thereof, wherein the figure shows a plan view of a lady's handkerchief showing my new design.

I claim:

The ornamental design for a lady's handkerchief, as shown.

MURRAY MORENSTEIN.
